UNITED STATES PATENT OFFICE.

NEVIN G. WOODSIDE, OF PITTSBURGH, PENNSYLVANIA.

DESIGN FOR A DISPENSING-RECEPTACLE AND DISPLAY-STAND.

45,362.

Specification for Design.

Patented Mar. 3, 1914.

Application filed December 26, 1913. Serial No. 808,916. Term of patent 14 years.

To all whom it may concern:

Be it known that I, NEVIN G. WOODSIDE, a citizen of the United States, residing at Pittsburgh, in the county of Allegheny and State of Pennsylvania, have invented a new, original, and ornamental Design for a Dispensing-Receptacle and Display-Stand, of which the following is a specification, reference being had to the accompanying drawing, forming part thereof.

The drawing shows a perspective view of the dispensing receptacle and display stand.

I claim:

The ornamental design for a dispensing receptacle and display stand, as shown.

NEVIN G. WOODSIDE.
